UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

METHOD OF PRODUCING HEAT-EXCHANGE UNITS

Application filed March 25, 1927. Serial No. 178,488.

My invention relates to heat exchange units and a method of producing the same and has among its other objects the production of devices of the kind described which are neat and attractive in appearance, compact, convenient, durable, efficient and satisfactory for use wherever found applicable.

5 A particular object of the invention is to provide an improved method for producing heat exchange units adapted to be employed as radiators or condensers.

10 Another particular object of the invention is to provide a heat exchange unit of improved construction.

15 Many other objects and advantages of the construction herein shown and described will be obvious to those skilled in the art from the disclosure herein given.

20 To this end my invention consists in the novel construction, arrangement and combination of parts herein shown and described, and more particularly pointed out in the claims.

25 In the drawings, wherein like reference characters indicate like or corresponding parts:

30 Fig. 1 is a perspective view of one of a plurality of tubes which form parts of a heat exchange unit embodying the invention;

35 Fig. 2 is a perspective view of one of a plurality of fins or plates which form parts of the improved heat exchange unit;

40 Fig. 3 is a perspective view of one of a plurality of U-shaped members which also form parts of the improved heat exchange unit;

45 Fig. 4 is a plan elevation of an assembly comprising members of the type shown in Figs. 1, 2 and 3;

50 Fig. 5 is a front elevation of the assembly shown in Fig. 4, a portion of a saw being shown in connection therewith to illustrate the manner in which my improved method is practiced;

55 Fig. 6 is a plan elevation of a heat exchange unit which has been formed by sawing through an assembly of the kind shown in Figs. 4 and 5; and

Fig. 7 is a front elevation of the heat exchange unit shown in Fig. 6.

It is believed that a complete understanding of my improved method will be had from the following description of a device which is manufactured by practicing the method.

The improved method is particularly adapted to be practiced in the manufacture of radiator units of the type shown and described in Patents 1,726,360, August 27, 1929 and 1,730,470, October 8, 1929 respectively, but it is to be understood that my invention is limited to this use only to the extent indicated in the appended claims as the units may be employed as condensers, or the like.

Figs. 1, 2 and 3 illustrate the construction of tubes, plates and U-shaped members, respectively, which constitute the assembly shown in Figs. 4 and 5, the tubes, plates and U-shaped members being identified by the reference characters 10, 11 and 12, respectively.

In the illustrated embodiment of the invention, the tubes 10 are of elongated cross section and are preferably formed from relatively thin sheet metal, the tubes being adapted to be inserted in apertures 14 provided in the plates 11.

The plates or fins 11 may be of any suitable construction but are also preferably formed from relatively thin sheet metal and are preferably provided with notches 16 in which the U-shaped members 12 may be secured.

It will be noted that the notches 16 are arranged in pairs so that when the U-shaped members 12 are assembled with the plates 11 in the manner illustrated in Fig. 4, each member 12 upon each face of the radiator will be aligned with a member 12 upon the other face thereof.

In practice, the tubes 10 are first assembled with the plates 11, the plates being retained in spaced relation during the assembling operation. After the tubes have been assembled with the plates, the U-shaped members 12 are inserted in the notches 16. The tubes 10 and U-shaped members 12 are preferably soldered to the plates 11. If desired, the tubes 10 may be soldered to the plates 11 by dipping them into a bath of fused

solder, and the U-shaped members 12 may be subsequently soldered to the plates in the same manner. Of course, in some instances, I may prefer to secure the U-shaped members 12 and the tubes 10 to the plates in a single operation by dipping them in fused solder, and in other instances I may prefer to secure the U-shaped members to the plates 11 by using soldering irons, or the like.

Assuming now that the tubes 10, the plates 11 and the U-shaped members 12 have been assembled as illustrated in Figs. 4 and 5, it is obvious that the unit may be cut along the dotted lines shown at 20 in Fig. 4 to provide a plurality of units substantially identical to the unit shown in Figs. 6 and 7. Any suitable means may be provided for cutting the assembly shown in Figs. 4 and 5 but I preferably employ a saw 21, or the equivalent, as indicated in Fig. 5 for this purpose. Obviously, after the saw has been employed to cut the assembly up into units, each unit will appear substantially as shown in Figs. 6 and 7 and will be provided with reinforcing strips 12^a at the corners of the plates 11. I have deemed it best to indicate the plates 11 in Figs. 6 and 7 by the same reference character as the plates shown in Figs. 2, 4 and 5 as substantially no change is made therein during the cutting operation with the exception that each of the larger plates is manufactured into a plurality of smaller plates.

The provision of the U-shaped members 12 which are formed into the reinforcing members 12^a is advantageous in that it prevents the production of a plurality of sharp, ragged corners upon each of the plates 11 in the sections, each unit having a neat and attractive appearance after it has been produced by sawing up the assembly shown in Figs. 4 and 5. It is readily apparent that the reinforcing members 12^a protect the edges of the plates 11 from injury and tend to retain them in their spaced positions. A feature of my invention is that the U-shaped members 12 serve as guides for the saw.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A method of forming heat exchange units which comprises forming an assembly of a plurality of plates and tubes, the plates being provided with guide means and then cutting through said assembly at said guide means to provide a plurality of units.

2. A method of forming heat exchange

units which comprises forming an assembly of a plurality of plates and tubes, securing guide means to said plates, and then sawing through said guiding means and said plates to divide the assembly into a plurality of units.

3. A method of forming heat exchange units which comprises forming an assembly of a plurality of plates and tubes, securing substantially U-shaped members to said assembly, and then sawing through said substantially U-shaped members and the plates to divide the assembly into a plurality of units.

4. A method of forming heat exchange units which comprises forming an assembly of a plurality of plates and tubes, soldering guide means to said assembly, and then cutting through said guide means and plates to divide the assembly into a plurality of units.

5. A method of forming heat exchange units which comprises forming an assembly of parts, securing guide means to said assembly, and then cutting through said assembly at said guide means to divide the assembly into a plurality of units.

6. A method of forming heat exchange units which comprises forming an assembly of a plurality of parts, soldering guide means to said parts, and then cutting through said assembly at said guide means to divide the assembly into a plurality of units.

7. A method of forming heat exchange units which comprises forming an assembly of parts, soldering members to said assembly, and then employing said members as guides to cut up the assembly into units.

In testimony whereof, I have hereunto signed my name.

ARTHUR B. MODINE.
